CLAIM

The ornamental design for a cap with drink-thru lid, as shown and described.

DESCRIPTION

FIG. 1 is a front perspective view of a cap with drink-thru lid in a closed position showing our new design;
FIG. 2 is a front elevational view of the cap with drink-thru lid;
FIG. 3 is a rear elevational view of the cap with drink-thru lid;
FIG. 4 is a right-side elevational view of the cap with drink-thru lid;
FIG. 5 is a left-side elevational view of the cap with drink-thru lid;
FIG. 6 is a top view of the cap with drink-thru lid;
FIG. 7 is a bottom view of the cap with drink-thru lid;
FIG. 8 is a rear perspective view of the cap with drink-thru lid;
FIG. 9 is a front perspective view of the cap with drink-thru lid in an opened position; and,
FIG. 10 is a rear perspective view of the cap with drink-thru lid in an opened position.
The broken lines in the drawing depict environmental subject matter only and form no part of the claimed design.

1 Claim, 9 Drawing Sheets
